UNITED STATES PATENT OFFICE.

STELLA B. DICKINSON, OF BELLEVILLE, NEW JERSEY, ASSIGNOR TO GINZKEY-MAFFERSDORF, INC., A CORPORATION OF NEW YORK.

DESIGN FOR A RUG.

Application filed February 6, 1926. Serial No. 16,436. Term of patent 3½ years.

To all whom it may concern:

Be it known that I, STELLA B. DICKINSON, a citizen of the United States of America, and resident of the city of Belleville, county of Essex, and State of New Jersey, have invented a new, original, and ornamental Design for a Rug, of which the following is a specification, reference being had to the accompanying drawing, forming part thereof.

The figure is a plan view of a rug, illustrating my new and ornamental design.

I claim:

The ornamental design for a rug as shown.

STELLA B. DICKINSON.
